UNITED STATES PATENT OFFICE.

HARRY R. NELSON, OF ELIZABETH, NEW JERSEY.

ELECTROLYTIC CELL.

1,149,210.

Specification of Letters Patent. Patented Aug. 10, 1915.

Application filed August 17, 1914. Serial No. 857,087.

To all whom it may concern:

Be it known that I, HARRY R. NELSON, a citizen of the United States of America, residing at Elizabeth, county of Union, State 5 of New Jersey, have invented certain new and useful Improvements in Electrolytic Cells, of which the following is a specification.

This invention relates to improvements in 10 electrolytic cells.

More particularly, this invention has for its object the provision of simple means for the electrolysis of suitable electrolytes, such as solutions of sodium chlorid, etc., whereby 15 the electrolysis is carried out under maximum efficiency, with the minimum attention and longest life of the parts of the electrolytic cell. In the usual form of my invention, the electrolytic cell proper comprises 20 a diaphragm disposed at or adjacent the sides and bottom of the cell proper, a cathode member surrounding the outer side of the diaphragm, and an anode member within the electrolytic cell thus formed. 25 The cathode member is preferably perforated or reticulated to permit the passage therethrough of the cathion.

I have discovered that the efficiency of the electrolysis of such solutions as of sodium 30 chlorid is markedly improved by supplying an atmosphere of steam or other suitable medium in proximity to the outer side of the cathode member. Preferably such atmosphere of steam or the like, is effected by 35 means of a casing or chest having suitable inlet and outlet means with the provision of proper controlling devices to regulate the supply of the steam and the discharge of the resulting reaction products. When a 40 solution of sodium chlorid of suitable concentration is run into an electrolytic cell embodying my invention, the cathion sodium resulting upon electrolysis combines with steam or the like as the cathion passes 45 through or emerges from the perforations or reticula of the cathode member, thereby forming caustic soda of high concentration with hydrogen. The resulting caustic soda trickles down the outer side of the cathode 50 member and is caught in a suitable receptacle, preferably a tiltable pan operated to tilt its contents at desired intervals into a fixed pan from which the caustic soda may be discharged. The continuance of the 55 atmosphere of steam or like medium and the

prevention of undue sputtering of caustic produced by the bursting of the hydrogen bubbles, is facilitated by the provision of a metal screen disposed at a predetermined distance from the outer side of a cathode 60 member. Such metal screen may be properly spaced from the cathode member by L-plates or the like.

In the operation of the preferred form of my catalytic cell, the sodium chlorid or 65 other solution is supplied to the cell at a rate commensurate with the rate of electrolysis, so that a circulation of the sodium chlorid or other solution into and out of the cell is not required. Foreign and other 70 precipitated matter is caught at the bottom of the cell proper, preferably on a removable strip of asbestos or other suitable material. By such means, the foreign and other precipitated matter is readily removed 75 from the interior of the electrolytic cell without disturbing the diaphragm proper.

Other features and objects of my invention will be more fully understood from the following description and accompanying 80 drawings, in which—

Figure 1 is a side elevation, partly broken away, of an electrolytic cell embodying my invention; and Fig. 2 is a vertical sectional elevation on the line 2—2 of Fig. 1. 85

Referring more particularly to the drawings, the outer casing member 1 of iron or other suitable metal serves as a support for the electrolytic cell proper and has a chest for the steam or other medium as set forth 90 more fully hereinafter. The cell proper 2 is supported within said casing 1 as by longitudinally extending angle plates 3, 4, the cell proper 2 comprising the diaphragm 5 of asbestos or other suitable material is 95 shown as a sheet curved into a U-shape hung from said oppositely disposed angle plates 3, 4; the cathode member 6 of perforated or reticulated iron or other suitable electrically conducting material is also shown 100 as U-shaped and supported by riveting or the like from the positioning angle plates 3, 4. The diaphragm 5 is held in the desired position relative to the centrally disposed anode member 7 by the sides 8, 8, of the dome chlorin chamber 9, of slate or other non-conducting material. The anode member 7 is illustrated as comprising individual anodes carried by the upper wall 10 of the chlorin chamber 9. The diaphragm 5 is 105 110

preferably secured to the respective angle plates 3, 4, by a lute of Portland or other suitable cement.

The positive side of the circuit is connected to the bus bar 11 connecting the several anodes of anode member 7. The negative side of the circuit is led to the cathode member 6 through the bus bar 12.

The upper ends of the opposite lateral portions of the casing 1 are made gas-tight by the cover members 13, 13, and the oppositely disposed inlet pipes 14, 15, are provided for the supply of steam or other suitable medium from a suitable source thereof. The flow of the steam or other medium is controlled by the valves 16. On the outer side of the cathode member 6 are arranged the oppositely disposed screens 17, 18, held in the angle plates 19, 19, and supported by the strips 20.

At the bottom of the cell proper 2 are provided the two strips 21 of curved asbestos or like material and properly positioned to catch the precipitated matter. When the precipitated matter has accumulated, the strips 21 may be taken out of the cell after the anode member 7 has been removed to permit access to the strips 21. Instead of a number of strips 21, the precipitate collecting means may be formed of a single strip of asbestos or the like slightly bent at the side to form a pan-like structure.

The tilting pan 22 shown disposed below the cathode member 6 collects the concentrated caustic soda; the particular tilting pan 22 is shown pivoted at opposite pivots 23 insulated from casing 1 and other parts of the cell; the pan 22 is tilted by suitable operating means to empty when the contents reach a predetermined amount. The caustic soda empties from the tilting pan 22 into the stationary pan 24 from which the caustic soda is discharged through the outlet 25.

Suitable provision is made for leading off the evolved hydrogen or other gas through the outlet pipes 26. Fig. 1 indicates an outlet pipe 26 on one side of the cell and a similar outlet pipe may be provided on the opposite side, the outlets for the hydrogen or other gas may be increased in number and disposed at suitable points.

The operation of my electrolytic cell will be more fully understood from the foregoing description taken in connection with the following explanations. Assuming the solution to be electrolyzed is a sodium chlorid solution, the same is supplied to the interior of the cell proper 2 as by means of the inlet pipes 29. The current is regulated for the proper voltage, whereby the chlorin evolved at the anode member 7 is collected within the chamber 9 and led out through the discharge opening 28 to a suitable reservoir or storage tank or the like. The cathion sodium encounters the steam supplied through

the inlet pipes 14, 15 and forms caustic liquor of high concentration with the evolution of hydrogen. The pressure of the steam at the inlet pipes 14, 15 is such as to maintain a "faint" cloud within the casing 1. The evolved hydrogen passes upwardly along the outer side of the cathode member 6 and is discharged through the outlets 26. Such atmosphere of steam within the casing 1 maintains the exterior of the cell proper 2 at steam temperature or thereabout, thereby reducing the heat losses of the bath to a minimum. The current density is kept at such value that the quantity of the resulting cathion set free is commensurate with the amount of steam supplied exteriorly of the cathode member 6. The formed caustic liquor trickles down the exterior of the cathode member 6 into the tilting pan 22 and is discharged therefrom intermittently into the pan 24. By the use of outlet pipes 26 for the steam or like medium in combination with the inlet pipes 14, 15, a circulation of the steam is effected by means of a suitable pump and steam supplying means.

It is preferred to admit "dry" steam through inlet pipes 14, 15, and for such purpose means such as the trap 31 is provided for collecting the condensed water or other liquid; also the inlet pipes and other parts of the steam supplying system may be provided with heat-insulating sleeves to prevent condensation of the vapor. In the event that water or other moisture be condensed within the casing 1 as by contact with the sides of casing 1, such condensed moisture will be caught at the bottom of the casing 1, and may be drained through outlets 30, 30. It will be noted that the mesh of the screens 17, 18, is chosen to catch substantially all of the cathode product which is "sputtered" by the bursting of the evolved gaseous reaction product, while at the same time the mesh freely admits the steam and maintains a uniform atmosphere adjacent the exterior side of the cathode. As shown, the lower angle bars 19, 19, are disposed in proper relation to the tilting pan 22 to direct the "caught" cathode product from the screens 17, 18, to the pan 22.

Whereas I have described my invention by reference to specific forms thereof, it will be understood that many changes and modifications may be made without departing from my invention.

What I claim and desire to secure by Letters Patent is:—

1. In an electrolytic cell, the combination with an anode of a permeable cathode, a container surrounding an exterior side of said cathode, means for supplying steam to the interior of said container and collecting means for the liquid cathode product electrically insulated from said permeable cathode.

2. In an electrolytic cell, the combination with an anode of a permeable cathode, a container surrounding an exterior side of said cathode, means for supplying steam to the interior of said container and collecting means for the liquid cathode product electrically insulated from said permeable cathode, said steam supplying means including means for effecting the absence of condensed moisture from in the region of said cathode.

3. In an electrolytic cell, the combination with an anode of a U-shaped permeable cathode, a container surrounding an exterior side of said cathode, means for supplying dry steam to the interior of said container and collecting means for the liquid cathode product disposed within the container and electrically insulated from said cathode.

4. In an electrolytic cell, the combination with an anode of a permeable cathode, a container surrounding an exterior side of said cathode, means for supplying to the interior of said container a gaseous medium capable of producing a liquid product with the cathion, and means for collecting such liquid reaction product within said container, said means being disposed below and spaced from said cathode and electrically insulated from said cathode.

5. In an electrolytic cell, the combination with an anode of a permeable cathode, a container surrounding an exterior side of said cathode, means for supplying to the interior of said container a gaseous medium capable of producing a liquid product with the cathion, and a tilttable pan for collecting such resulting liquid product disposed at a distance below said cathode.

6. In an electrolytic cell, the combination with an anode, of a permeable cathode extending substantially in a vertical plane, a container surrounding an exterior side of said permeable cathode, means for supplying steam to the interior of said container, said steam supplying means including means for withdrawing condensed moisture from proximity to said cathode, and a tilttable pan disposed below said cathode for collecting the resulting product at a point remote from said cathode.

7. In an electrolytic cell, the combination with an anode, of a permeable cathode, a container surrounding an exterior side of said permeable cathode, means disposed within said container for preventing the dispersion of products evolved at said cathode and collecting means for the liquid cathode product disposed within said container and electrically insulated from said cathode.

8. In an electrolytic cell, the combination with an anode, of a permeable cathode, a container surrounding an exterior side of

said permeable cathode, means for supplying steam to the interior of said container, means disposed in said container for preventing the dispersion of the evolved cathode product and collecting means for the liquid cathode product electrically insulated from said permeable cathode.

9. In an electrolytic cell, the combination with an anode, of a permeable cathode, a container surrounding an exterior side of said permeable cathode, means for supplying steam to the interior of said container, permeable means disposed in said container for preventing the dispersion of the evolved cathode product and collecting means for the liquid cathode product disposed within said container and electrically insulated from said cathode.

10. In an electrolytic cell, the combination with an anode, of a bent permeable cathode, a container surrounding an exterior side of said permeable cathode, means for supplying a gaseous medium to the interior of said container, means disposed within said container for preventing the dispersion of the evolved liquid cathode product, outlet means for the gaseous cathode product and collecting means for the liquid cathode product electrically insulated from said cathode and said preventing means.

11. In an electrolytic cell, the combination with an anode, of a bent permeable cathode, a container surrounding an exterior side of said permeable cathode, means for supplying a gaseous medium to the interior of said container, means disposed within said container for preventing the dispersion of the evolved liquid cathode product, and means for collecting the cathode product, said last-named means being disposed below said cathode and electrically insulated from said cathode.

12. In an electrolytic cell, the combination with an anode, of a permeable cathode, a container surrounding the exterior side of said cathode, means disposed within said container for collecting the liquid cathode product and electrically insulated from said cathode, a second means for collecting the cathode product disposed below said first named means, and means for emptying said first named collecting means into said second-named collecting means.

13. In an electrolytic cell, the combination with a permeable cathode having a substantially U-shape, a container surrounding the exterior sides of said cathode, a screen disposed within said container and adjacent but spaced from an exterior side of said cathode, and collecting means for the liquid cathode product electrically insulated from said cathode.

14. In an electrolytic cell, the combination with a substantially U-shaped permeable cathode, of a container surrounding the ex-

terior sides of said cathode, permeable means disposed within said container adjacent but spaced from an exterior side of said cathode, and collecting means for the liquid cathode product disposed in operative relation to said cathode and said permeable means, said collecting means being electrically insulated from said cathode and said permeable means.

15. In an electrolytic cell, the combination 10 with a permeable cathode, of a container surrounding the exterior side of said cathode, means for supplying to the interior of said container a heated gaseous medium capable of reacting with the cathion set free 15 upon electrolysis collecting means for the cathode product disposed within said container and electrically insulated from said cathode, means for leading off from said gaseous medium condensed material prior to 20 the entry of said gaseous medium within said container and means for leading off condensed material from the gaseous medium within said container.

16. In an electrolytic cell, the combination 25 with an anode, of a cathode, a container surrounding an exterior side of said cathode, means for supplying a gaseous medium to the interior of said container, collecting means for the liquid cathode product disposed within said container and electrically insulated from said cathode and means for leading off condensed material from the gaseous medium.

17. In an electrolytic cell, the combination 35 with an anode, of a permeable cathode, a container surrounding an exterior side of said permeable cathode, permeable means disposed within said container but electrically insulated from said permeable cathode 40 for preventing the dispersion of liquid cathode product and collecting means for the liquid cathode product electrically insulated from said permeable cathode.

18. In an electrolytic cell, the combination 45 with an anode, of a permeable U-shaped cathode, a container surrounding the exterior sides of said permeable cathode, means for supplying steam to the interior of said container, means disposed within said container 50 but electrically insulated from said cathode

for preventing the dispersion of evolved liquid cathode product, collecting means for the liquid cathode product disposed below said dispersion preventing means and electrically insulated from said cathode, and 55 outlet means for the gaseous cathode product disposed above said collecting means and above said cathode and said dispersion preventing means.

19. In an electrolytic cell, the combination 60 with an anode, of a permeable cathode, a container surrounding the exterior side of said cathode, means for supplying steam to substantially the entire superficial area of said cathode, collecting means for the liquid portion of the cathode product disposed within said container and electrically insulated from said cathode, a second collecting means for the liquid portion of the cathode product arranged within said container, and 65 means for intermittently discharging said first named collecting means into said second named collecting means.

20. In an electrolytic cell, the combination 70 with an anode, of a permeable U-shaped 75 cathode, a container surrounding the exterior sides of said cathode, steam supplying means communicating with the interior of said container, and collecting means for the liquid portion of the cathode product 80 disposed within said container below said cathode and having all of its sides extending upwardly to points below the lowest point of said cathode.

21. In an electrolytic cell, the combination 85 with an anode, of a permeable cathode, a container surrounding an exterior side of said cathode, means for supplying a gaseous medium to the interior of said container, and means disposed within said container 90 for collecting the liquid portion of the cathode product out of contact with said cathode.

In testimony whereof I have signed this specification in the presence of two subscribing witnesses.

HARRY R. NELSON.
